NORMAL HEXANE AND CYCLO- HEXANE PRODUCTION

Walter O. Schellenberg, Sweeny, Tex., assignor to Phillips
Petroleum Company, a corporation of Delaware
Filed May 13, 1963, Ser. No. 279,776
1 Claim. (Cl. 260—666)

This invention relates to the production of normal hexane. In one aspect the invention relates to the recovery of normal hexane from a petroleum fraction containing close-boiling constituents wherein the benzene therein is hydrogenated and the effluent therefrom is subsequently subjected to isomerization conditions to isomerize methylcyclopentane to cyclohexane.

Naturally occurring cyclohexane hydrocarbon fractions are very difficult to separate by fractionation from other close-boiling constituents such as the dimethylpentanes, cyclohexane, normal hexane, isohexanes, benzene and methylcyclopentane.

A proposed method for effecting the production of high purity cyclohexane from a naturally occurring petroleum fraction containing a mixture of close-boiling hexane constituents is by the isomerization of the methylcyclopentane to cyclohexane. It is common practice to first treat the feed to the isomerization unit for the removal of isohexanes, naturally occurring cyclohexane and other impurities to leave normal hexane, methylcyclopentane and benzene. The benzene is then hydrogenated under benzene-hydrogenation conditions to cyclohexane with the effluent therefrom being the feed to the isomerization unit. Heretofore, it has been the practice to recover the methylcyclopentane from the isomerization unit effluent and then subsequently recover the normal hexane therefrom as product. However, the normal hexane is isomerized in the isomerization unit to isohexanes, thereby reducing the amount of normal hexane recoverable.

It is an object of the invention to provide an improved process for the recovery of normal hexane.

It is another object of the invention to provide an improved process for the isomerization of methylcyclopentane to cyclohexane.

It is yet another object of the invention to provide an improved process for the hydrogenation of benzene to cyclohexane.

These and other aspects of the invention will readily be apparent to those skilled in the art from the accompanying disclosure, appended drawing and claim.

These objects are broadly accomplished by treating a benzene hydrogenation zone effluent containing normal hexane, methylcyclopentane, cyclohexane, and isohexanes so as to recover therefrom a fraction comprising normal hexane and isohexanes and leaving a second fraction comprising methylcyclopentane and cyclohexane with the normal hexane product being separated from the isohexane. The second fraction is then passed to an isomerization zone under conditions wherein the methylcyclopentane is isomerized to cyclohexane with the cyclohexane being subsequently recovered.

In one embodiment the methylcyclopentane recovered from the isomerization zone effluent is recycled to the feed to the hydrogenation unit.

The invention is best illustrated by the following drawing.

The drawing is a schematic illustration of the preferred embodiment employing the invention in the hydrogenation of a natural cyclohexane-containing feed also containing benzene and the subsequent isomerization of the methylcyclopentane in the hydrogenation effluent.

A feed which has preferably been depentanized and deheptanized and comprising naturally occurring cyclohexane, normal hexane, methylcyclopentane, benzene and isohexanes is passed through conduits 2 and 4 into deisohexanizer 6 wherein the isohexanes are removed overhead through conduit 8. The bottoms from the deisohexanizer 6 are passed through conduit 10 into demethylcyclopentanizer 12. The cyclohexane and heavier products are removed as bottoms through conduit 16 for passage into a separate process. The overhead 14 contains basically methylcyclopentane, lighter hydrocarbons, and a small amount of benzene which are introduced into the hydrogenation unit 18. Within this hydrogenation unit, the benzene is hydrogenated to cyclohexane in the presence of hydrogen with a suitable benzene hydrogenation catalyst such as nickel on kieselguhr, such as described in U.S. Patent No. 2,906,784, issued September 29, 1959. The preferred catalyst is nickel-on-kieselguhr, the nickel content ranging from about 20 to about 55 weight percent of the catalyst. Preferably the temperature is maintained within a range of 370 to 550° F. with a pressure in the range of 400-600 p.s.i.g. The effluent from the hydrogenation unit 18 is then treated to remove hydrogen by passage through conduit 20 into a fractionator 22 wherein the hydrogen is removed overhead through conduit 24. The bottoms are removed through conduit 26 and are treated to remove the normal hexane by the method of this invention. Heretofore, it has been the practice to pass the hydrogenation effluent directly into the isomerization unit and then subsequently recover the normal hexane as solvent therefrom. However, this has the disadvantage of reducing the recoverable normal hexane since the normal hexane is isomerized to isohexanes within the isomerization unit. By the method 30 of this invention the hydrogenation unit effluent is passed through conduit 26 into dehexanizer 28 wherein the overhead product containing most of the isohexanes and normal hexane are removed through conduit 30 and passed into the deisohexanizer 32. The conditions are maintained therein suitable for the distillation of the isohexanes overhead through conduit 34. The normal hexanes are removed as bottoms through conduit 36 and as a product. The bottoms from the dehexanizer 28 are passed through conduit 38 into an isomerization unit 40 wherein the methylcyclopentane is isomerized to cyclohexane. This isomerization unit is maintained under suitable conditions for the isomerization step and usually employs a catalyst such as a catalyst of the platinum type, such as platinum-alumina promoted with chlorine or fluorine. A particularly suitable catalyst is the Penex catalyst which is a platinum containing catalyst with alumina or another noble catalyst from the platinum group, such as ruthenium, rhodium, palladium, osmium, iridium, and platinum promoted by a minor amount of a combined halogen. Preferably, the catalyst comprises a composite of alumina and platinum with the platinum being in a concentration of from 0.01 to about 5 percent by weight of the catalyst and more particularly a composite of alumina, platinum and combined halogen, preferably fluorine. The catalyst may be in the form of a powder, or larger size granules or may be regular size and shape. Other suitable catalyst may be employed such as the aluminum halide type promoted by hydrogen chloride or the like.

40 When employing the Penex catalyst the temperature is preferably in the range of 650 to 750° F. with a pressure in the range of 400 to 550 p.s.i.g. and is sufficient to promote the isomerization of the methylcyclopentane to cyclohexane. The effluent from the isomerization unit is principally a mixture of methylcyclopentane and cyclohexane with smaller quantities of normal hexane and isohexanes. The effluent is passed through conduit 42 into

demethylcyclopentanizer 44 wherein the cyclohexane product is separated and withdrawn as bottoms through conduit 46. In one preferred embodiment of the invention, the methylcyclopentane-containing fraction is removed overhead through conduit 48 and back into the feed to the deisohexanizer 6 which is subsequently fed to the hydrogenation unit 18.

By the method of this invention, the production of normal hexane is increased due to a decrease in the isomerization of the normal hexane in the isomerization unit 10 to isohexanes. In addition, by recycling the methylcyclopentane to the hydrogenation unit feed the isohexanes therein are removed.

A material balance of one specific embodiment of the

third fraction containing cyclohexane from said second fraction leaving a fourth fraction containing n-hexane, methylcyclopentane and benzene, passing said fourth fraction through a hydrogenation zone under hydrogenation conditions sufficient to hydrogenate said benzene to cyclohexane, recovering a fifth fraction containing n-hexane and isohexane from the effluent from said hydrogenation zone and leaving a sixth fraction containing methylcyclopentane, recovering n-hexane product from said fifth fraction, passing said sixth fraction through an isomerization zone maintained under isomerization conditions sufficient to isomerize methylcyclopentane to cyclohexane, recovering cyclohexane product from the isomerization zone effluent leaving a seventh fraction con-

invention is presented in the following table to better illustrate the invention.

While certain examples, structures, composition and process steps have been described for purpose of illustration, the invention is not limited to these. Variation and modification within the scope of the disclosure and the claim can readily be affected by those skilled in the art.

I claim:

A process for the recovery of n-hexane from a feed containing methylcyclopentane, benzene, isohexanes, n-hexane, and cyclohexane comprising recovering a first fraction containing isohexane from said feed in a deisohexanizing zone leaving a second fraction containing methylcyclopentane, benzene, n-hexane and cyclohexane, recovering

taining methylcyclopentane, and recycling said seventh fraction to said deisohexanizing zone.
